CONDIMENT INJECTOR

Darrell R. Shipley, Box 2037,
Clarksville, Tenn. 37040

Filed Apr. 18, 1968, Ser. No. 11,519

Term of patent 14 years

Int. Cl. D7—99

U.S. Cl. D44—29

Fig. 1

Fig. 2

FIG. 1 is a front elevational view of a condiment injector showing my new design;

FIG. 2 is a top plan view; and

FIG. 3 is a bottom plan view.

The side of the condiment injector opposite to that shown in FIG. 1 is plain and unornamented.

I claim:

The ornamental design for a condiment injector, as shown and described.
